United States Patent Office

Des. 205,447
Patented August 9, 1966

205,447

HOUSE

Donald D. Burris, Wayne, Pa., assignor to Certain-Teed
Products Corporation, Ardmore, Pa., a corporation of Maryland

Filed Nov. 19, 1965, Ser. No. 88,160

Term of patent 14 years

(Cl. D13—1)

The dominant features of my design reside in the portions shown in full lines.

I claim:

The ornamental design for a house, as shown and described.
